CLAIM

The ornamental design for a lens insert for head-mounted display, as shown and described.

DESCRIPTION

FIG. 1 is a front and left perspective view of a lens insert for head-mounted display;

FIG. 2 is a front view thereof;

FIG. 3 is a rear view thereof;

FIG. 4 is a left view thereof;

FIG. 5 is a right view thereof;

FIG. 6 is a bottom view thereof; and,

FIG. 7 is a top view thereof.

The broken lines in the drawings are included for the purpose of illustrating portions of the article that form no part of the claimed design.
